SPARK PLUG

Theodore Irvin and John A. Pearce,
Philadelphia, Pa.

Application August 18, 1931, Serial No. 557,892

4 Claims. (Cl. 123—169)

This invention relates to an improved spark plug, and more especially to a spit fire type, wherein the lower end of the casing of the spark plug, that is the casing for the reception of the porcelain holder for the electrode is closed over the electrode, with the exception of providing two diametrically opposite openings in the closed end of the casing to provide outlets, through which the exploded gases collected in a chamber caused

10 to be formed in the lower end of the casing adjacent the terminal of the electrode may escape.

It is to be understood that the particulars herein given are in no way limitative, and that while still keeping within the scope of the invention, 15 any desired modification of details and proportions may be made in the construction of the appliance according to circumstances.

The invention comprises further features and combination of parts to be hereinafter set forth, 20 shown in the drawing and claimed.

In the drawing:—

Figure 1 is a vertical sectional view through the improved spark plug constructed in accordance with the invention.

25 Figure 2 is an end view showing the diametrically opposite openings for the escape of the exploded gases.

Figure 3 is an enlarged detail perspective view of the lower end of the casing of the spark plug 30 more clearly showing the diametrically opposite openings.

Referring to the drawing 1 identifies a casing of the spark plug, which may be made of any suitable metal, for housing a porcelain holder 2, 35 which in turn supports an electrode 3. This casing is provided with threads 5 for engaging a tapped opening 6 formed in the wall of the combustion chamber of an internal combustion engine (not shown). The porcelain holder, while 40 it may be of any desired exterior contour is preferably provided with a conical portion 7 merging into a shoulder 8, against which a ring 9 of any suitable metal preferably copper may engage. A nut 10 fits telescopically over the upper end 45 of the porcelain holder and against the ring and is provided with exterior threads 11, for engagement with the internal threads 12 of the spark plug casing. The electrode is made of any suitable electrical conducting metal, and has its terminal spaced a short distance from a screw terminal 13, which is threaded in the lower end of the spark plug casing so as to provide a sparking gap. Also threaded in to the lower end of the spark plug casing is a lock screw 14, which retains the screw terminal in locked position. A

ring 15 of any suitable metal preferably copper is located interiorly of the spark plug casing and against which the porcelain holder engages. The end 16 of the spark plug casing is closed and has a pair of diametrically opposite openings 17, which are positioned on an angle, due to the closed end of the spark plug casing being conical. By this construction and arrangement of spark plug casing relative to a copper ring adjacent the inner end of the porcelain holder the gas chamber 18 is 10 caused to be formed, and into which the usual gas charge on the interior of the combustion chamber is compressed, on the compression stroke of the piston (not shown) of the engine (not shown), whereby when a charge of current passes across 15 the gap between the terminal of the electrode and the screw terminal the compressed gases are exploded.

In this case the exploded gases discharge through the diametrically opposite openings, and 20 thereby impart movement to the engine piston due to the force of the explosion and the expanded gases. By this construction and arrangement the spark plug obviously as characterized 25 is the spit fire type.

The invention having been set forth, what is claimed is:

1. In a spark plug, the combination with a casing provided with a substantially closed end, the wall of said closed end being of an abrupt 30 conical formation, of an electrode holder operatively fitting closely within the lower portion of said casing and carrying an electrode longitudinally centrally of the holder with an end protruding beyond the end of the holder, the end of 35 the holder being dished to expose a substantial portion of the end of the electrode; means within the casing between the end of the holder and the wall of said closed end acting to create a gas chamber between the end of the holder and the 40 wall of said closed end, and into which one end of the electrode terminates, a terminal screw threaded through the apex of the conical closed end constituting an opposite electrode axially aligned with the extremity of the first electrode 45 and being spaced therefrom causing a sparking gap to be formed, said terminal screw electrode being adjustable to increase or decrease the 50 sparking gap, a locking screw threaded through the apex of the conical closed end and against the terminal screw electrode to lock the latter in adjusted positions and against displacement incident to vibrations, said conical closed end having diametrically opposite discharge openings with their axis at direct right angles to 55

the conical wall of the closed end and at acute angles to the first electrode, whereby upon a compression of the discharge in the chamber with a subsequent explosion of the charge by a 5 spark across the gap, the exploded gases discharge divergently from the chamber and from the first electrode and away from the gap immediately incident to the gap thereby preventing collection of carbon in the gap and between 10 the adjacent ends of both electrodes.

2. In a spark plug, a casing provided with a substantially closed abrupt conical end, the inner surface of said end being substantially of a 15 simulating conical formation, a gasket conforming to and seated upon said inner simulating conical surface, said casing having a bore extending from said inner conical surface of the closed end for substantially one half the length of the casing, an electrode holder fitting closely 20 within substantially the full length of said bore with its inner end conforming to and engaging said gasket thereby spacing the inner end of the holder from said inner conical surface of the closed end creating a gas chamber, means co- 25 operating with the other end of the holder and casing for bearing the inner end of the holder tight against the gasket, thereby preventing any gases seeping between the holder and the bore of the casing, an electrode centrally of the 30 holder, a second electrode carried by the apex of said closed end and its end spaced from the first electrode to create a sparking gap, said closed end of the casing having opposite discharge 35 openings with their axis substantially at right angles to the conical wall of the closed end and at acute angles to the first electrode, whereby upon an explosion of the charge in the chamber, the gases discharge divergently from the chamber and away from the gap between the first and 40 second electrodes.

3. In a spark plug, a casing provided with a substantially closed abrupt conical end and having a bore extending from said end for substantially one half the length of the casing, an electrode holder fitting within substantially the full 5 length of the bore with its inner end spaced from the inner surface of the closed end creating a gas chamber, means for preventing seeping of gases between the wall of the bore and the holder, an electrode centrally of the holder with its inner end exposed in said gas chamber, a screw electrode threaded through the apex of the closed end, a locking screw threaded into said apex against and locking the second electrode in spaced relation to the first electrode to create a 10 15 sparking gap in said chamber, said closed end having opposite openings with their axis substantially at right angles to the wall of the closed end and at acute angles to the first electrode, whereby upon an explosion of the charge in the 20 chamber the gases may discharge divergently away from the gap and through the openings.

4. A spark plug comprising a casing, and means for installing said casing in the cylindrical wall of an internal combustion engine with 25 one end exposed in the cylinder, said casing having in the interior thereof an enclosed firing chamber, and having in the exposed end thereof a plurality of ports which enter the firing chamber in divergent positions therefrom at diametrically opposite points of the center of the bottom 30 wall of the chamber, sparking terminals exposed in this firing chamber, one being in the center of the bottom wall of the chamber between the ports, and a locking plug fastened in the center 35 of the bottom wall of said chamber against one of said sparking terminal elements to lock the latter in position.

THEODORE IRVIN.
